UNITED STATES PATENT OFFICE.

HERMAN IHLENBURG, OF PHILADELPHIA, PENNSYLVANIA, ASSIGNOR TO THE
MACKELLAR, SMITHS & JORDAN COMPANY, OF SAME PLACE.

DESIGN FOR A FONT OF PRINTING-TYPE.

SPECIFICATION forming part of Design No. 22,020, dated November 29, 1892.

Application filed October 28, 1892. Serial No. 450,289. Term of patent 7 years.

To all whom it may concern:

Be it known that I, HERMAN IHLENBURG, a citizen of the United States, and a resident of Philadelphia, Pennsylvania, have invented a new and original Design for a Font of Printing-Type, of which the following is a specification.

My design for a font of fancy-faced type is clearly shown in the accompanying typographical impression, to which reference is made.

The main feature of the design is the rounded appearance of the characters, and the lines of the type are shaped as if made by a quill-pen. Several of the letters in the font have circular terminations, particularly letters "A," "B," "E," "F," "I," "L," "P," "Q,"

"R," "S," "T," "U," "V," "Y," and "Z." The lower-case letters and numerals are in keeping with the upper-case letters. The numerals "2," "3," "5," and "7" have the circular terminals.

I claim—

The design for a font of type, substantially as described, and shown in the accompanying typographical impression.

In testimony whereof I have signed my name to this specification, in the presence of two subscribing witnesses.

HERMAN IHLENBURG.
